UNITED STATES PATENT OFFICE.

AUSTIN KIMBLE, OF WAUSAU, WISCONSIN, ASSIGNOR TO MARATHON ELECTRIC MFG. COMPANY, OF WAUSAU, WISCONSIN, A CORPORATION OF WISCONSIN.

INDUCTION-MOTOR.

1,375,461.

Specification of Letters Patent. Patented Apr. 19, 1921.

Application filed May 12, 1919. Serial No. 296,649.

To all whom it may concern:

Be it known that I, AUSTIN KIMBLE, a citizen of the United States of America, and a resident of Wausau, county of Marathon, and State of Wisconsin, have invented 5 certain new and useful Improvements in Induction-Motors, of which the following is a specification.

This invention relates to squirrel cage 10 structures for dynamo-electric machines, and to methods of forming same.

The main objects of the invention are to provide an improved form of conductor adapted to serve as a squirrel cage bar and 15 capable of readily transmitting large currents of low frequency or of non-alternating character, but offering relatively high impedance to alternating currents of high frequency; and to provide a squirrel cage 20 rotor having improved ventilating means.

An illustrative embodiment of this invention is shown in the accompanying drawings, in which—

Figure 1 is a longitudinal section on the 25 line 1—1 of Fig. 2, of a squirrel cage rotor, one side being broken away.

Fig. 2 is substantially an end view of the rotor with the shaft and the projecting ends of the squirrel cage bars shown in section on 30 the line 2—2 of Fig. 1.

In the construction shown in the drawings, the rotor comprises a laminated core 1 secured by threaded clamping rings 2 on the shaft 3. The squirrel cage carried by said 35 core includes a pair of end rings 4 and a peripheral series of bars 5 connecting said rings. Each bar 5 consists of a core 6 of high reactance metal and a coating or sheath of low impedance metal, cast-iron 40 rods being well adapted to serve as cores, and an electro-deposit of copper being best adapted to serve as the covering 7. The said bars are disposed in slots 8 and are secured to the end rings in a substantially integral 45 manner by any approved means, preferably brazing, as shown at 9.

The method of forming and assembling the several parts is as follows: The bars for the squirrel cage are cut in suitable lengths 50 from copper-plated stock, which may be supplied in any lengths which commercial convenience may determine. The cores are assembled in the usual manner as understood in the art, and the end rings 4 are ap-

plied thereto, after which the bars 5 are set 55 into place and arranged to project an equal distance at each end for ventilating purposes and are secured as above explained.

Although the compound bars 5 are not necessarily limited to the cylindrical sheath 60 and core form shown, still the concentric distribution of the copper about the iron is considered best, as it is most favorable to the transmission of high frequency current. This form is also advantageous as being 65 adapted for ready manufacture.

Although the core openings for the bars 5 are designated as "slots," it is to be understood that they may be of any approved form, including tubular perforations 70 disposed adjacent to the core surface.

The operation of the machine is as follows: In starting the motor, the bars offer a relatively high degree of impedance, due to the high frequency of the current which 75 tends to flow therein, but as the machine comes up to speed, the frequency diminishes until, at or near synchronism, the current becomes substantially constant and unidirectional, so that the reactance becomes 80 negligible and only the low ohmic resistance of the circuit has to be overcome.

Although but one specific embodiment of this invention has been herein shown and described, it will be understood that numerous 85 details of the construction shown may be altered or omitted without departing from the spirit of this invention as defined by the following claims.

I claim:

1. A squirrel cage winding comprising a pair of low impedance end rings, in combination with a peripheral series of compound bars connecting said rings, each bar including a core of high-reactance metal 95 and a covering of low impedance metal.

2. A squirrel cage motor device of the character described, comprising a laminated core with end rings thereon, and a series of compound connecting bars disposed in a 100 peripheral series on said core, each bar including an inner core of high-reactance material and an outer covering of low impedance material.

Signed at Chicago this 9th day of May, 105 1919.

AUSTIN KIMBLE.
